UNITED STATES PATENT OFFICE.

AUGUST J. FONDEVILLE, OF WEST HOBOKEN, NEW JERSEY.

DESIGN FOR A LAMP-SHADE.

SPECIFICATION forming part of Design No. 23,177, dated April 10, 1894.

Application filed March 7, 1894. Serial No. 502,779. Term of patent 3½ years.

To all whom it may concern:

Be it known that I, AUGUST J. FONDEVILLE, a citizen of the United States, residing at West Hoboken, in the county of Hudson and State of New Jersey, have invented and produced a new and original Design for Lamp-Shades, of which the following is a specification, reference being had to the accompanying drawing, forming a part thereof, and in which the lamp-shade constructed in accordance with and embodying my invention and design is illustrated in a perspective view.

The leading features of my design consist of a lamp shade having a series of horizontal sections each of which is fluted in line with the length of the shade, and the flutings of each section being in alternate arrangement with the flutings of the adjoining section or sections, whereby the apex of the flutings of one section terminates between the apices of the flutings of the adjoining section or sections and the meeting line between the sections forms a connected series of corresponding angular outlines imparting a harmonious and pleasing ornamental effect to the shade, as shown in the drawing.

The object of the invention is to produce a globular form of shade which over its entire surface will present sharp angular outlines and have a diamond cut effect.

In the accompanying drawing, A, B, C, D, respectively designate the horizontal sections of the lamp shade, each section being composed of flutings which are respectively lettered *a, b, c, d*. It will be observed that the apex of the flutings *a* terminates between the apices of the flutings *b*; that the apex of the flutings *b* terminates between the apices of the flutings *c*, and that the apex of the flutings *c* terminates between the apices of the flutings *d*; and that at the intersecting lines *e, f, g*, between the said sections A, B, C, D, are formed the connected series of cone-shaped outlines shown, the said outlines at the intersecting line *g* being inclined outward and downward, as illustrated, and adding to the general ornamental effect of the shade. The lower circumferential edge of the shade has the depending ornamental curtain or fringe *E*.

50

What I claim is—

The design for a lamp shade, substantially as shown and described.

Signed at the city of New York, in the county of New York, this 6th day of March, 55 1894.

AUGUST J. FONDEVILLE.
